UNITED STATES PATENT OFFICE.

JOHN ROCK, JR., OF HAMTRAMCK, MICHIGAN.

SHUTTER-OPENER.

1,280,553.

Specification of Letters Patent.

Patented Oct. 1, 1918.

Application filed July 11, 1918. Serial No. 244,408.

To all whom it may concern:

Be it known that I, JOHN ROCK, Jr., a citizen of the United States, residing at Hamtramck, in the county of Wayne, State 5 of Michigan, have invented a new and useful Shutter-Opener; and I do hereby declare the following to be a full, clear, and exact description of the invention, such as will enable others skilled in the art to which 10 it appertains to make and use the same.

The present invention relates to a shutter opening and closing device, and has for its object to provide a device of this character which embodies novel features of construction 15 whereby the shutters can be manipulated from the inside of a building without the necessity of opening the windows, thereby avoiding the necessity of letting a lot of cold air and rain into a building and 20 personally leaning out of a window when it is desired to close the shutters in bad weather.

Further objects of the invention are to provide a shutter opening device which can be used in connection with the conventional 25 shutters, which can be easily manipulated from the inside of the building, which is adjustable to fit different window structures, and which can be arranged to operate both 30 blinds simultaneously.

With these and other objects in view, the invention consists in certain novel combinations and arrangements of the parts as will 35 more fully appear as the description proceeds, the novel features thereof being pointed out in the appended claims.

For a full understanding of the invention, reference is to be had to the following description and accompanying drawings, in 40 which:—

Figure 1 is a transverse vertical sectional view through the lower portion of a window which is provided with blinds and blind operating means constructed in accordance 45 with the present invention.

Fig. 2 is a horizontal sectional view on the line 2—2 of Fig. 1, looking in the direction of the arrows, and showing the link connection between the operating gearing 50 of the two shutters.

Fig. 3 is an enlarged view of the shutter hinge, the two leaves thereof being shown as in an extended position and as connected to the window casing and shutter respectively,

Fig. 4 is an end view of that portion of the hinge which is secured to the shutter, showing the hinge knuckles and the downwardly extending socket which is rigid with the shutter engaging leaf of the hinge and 60 has the shutter operating shaft connected thereto.

Fig. 5 is a front elevation of the lower corner of a window provided with shutters which are adapted to be opened and closed 65 by a mechanism embodying the invention.

Fig. 6 is a similar view of the inside of the window.

Fig. 7 is a top plan view of the small sprocket wheel which engages the blind 70 operating shaft.

Fig. 8 is a sectional view through the same.

Corresponding and like parts are referred to in the following description and indicated in all the views of the drawings by the same reference characters.

Referring to the drawings, which illustrate one embodiment of the invention, the reference character A designates a window casing which is of the conventional construction, being provided with a sliding sash B and having a sill 1 at the bottom thereof which overhangs the outer face of the wall C, a recess D being provided in 85 the wall under the sill. A shutter E is hingedly connected to each side of the window casing A, said shutters being adapted to be swung inwardly to close the window opening or swung outwardly away from the same in the usual and well-known manner. The invention resides in the special means for mounting and operating the shutters, this mechanism enabling the shutters to be opened and closed from the interior of the building without the necessity of opening the windows.

The lower shutter hinges each include a pair of complementary hinge leaves 2 and 3 which are secured to the window casing A 100 and shutter E, respectively, the leaves being formed at their meeting edges with knuckles 4 which receive a pintle 5, and the leaf 3 which is rigidly secured to the edge of the shutter being constructed with a downwardly 105 extending recessed arm 6 which is arranged in alignment with the axis of the hinge so that by applying the necessary turning force to this arm 6 the hinge leaf 3 and shutter carried thereby can be swung back and 110

forth upon the axis of the hinge. Arranged under each of the shutter hinges is an upright shaft 7 which is shown as extending through the overhanging portion of the window sill 1, the lower end 7^a of the shaft having a square or polygonal formation and being slidably received within a corresponding opening in the hub of a sprocket wheel 8. These sprocket wheels 8 have the hubs 10 thereof journaled in bearings 9 which project outwardly from the wall C under the sill 1, the sprocket wheels and bearings being housed within substantially semispherical flanged casings 10 which are secured to 15 the wall and which are provided with upper and lower openings to receive the upright shafts 7. The upper ends of the shafts 7 are connected by a series of links 11 to the blind hinges, the upper links being fitted within 20 the recessed arms 6 of the respective hinges and held rigidly in position therein by suitable means such as the set screws 12, and the joints 11^a between the members having axes at substantially right angles to each 25 other so that a universal joint is provided between each of the upright shafts 7 and the upper link member which is connected to the corresponding shutter hinge. There will thus be no difficulty in operatively connecting the upright shafts 7 to the shutter hinges, even though the construction of the window casing or arrangement of the building may be such that it is impossible to mount the upright shafts directly under the axes of the 30 blind hinges. It will also be obvious that the sliding connection between the polygonal lower ends 7^a of the upright shafts and the hubs of the sprocket wheels 8 enable the sprocket wheels to be mounted at slightly 35 higher or lower elevations as may be necessary under different circumstances, without in any manner deranging or interfering with the proper connection being made with the blind hinges.

40 The sprocket wheels 8 under the two blinds are each connected by a sprocket chain 13 to a larger sprocket wheel 14 which is arranged within the recess D of the wall, the sprocket wheels 14 being mounted upon vertical shafts 15 which project downwardly from the top of the recess. The two wheels 14 are connected by a transverse link 16 which is housed within the recess D, the ends of the link being pivoted at 17 to the 45 respective wheels 14 on opposite sides of the centers thereof, and the end portions of the link being preferably curved, as indicated at 16^a, in such a manner as to provide clearance spaces for the shafts 15 and increase the rotation which can be imparted to the sprocket wheels before the link is brought into engagement with the shafts. Owing to the fact that the link is connected to the sprocket wheels 14 on opposite sides 50 of the respective shafts 15, it will be obvious

that a turning of one sprocket wheel in one direction will result in a corresponding rotation of the other sprocket wheel in the opposite direction. The two upright shafts 7 are thus simultaneously turned in opposite 70 directions when the mechanism is operated, thereby enabling the shutters E on opposite sides of the window casing A to be simultaneously opened and closed.

One of the sprocket wheels 14 has a bevel gear 18 rigid with the lower face thereof, said gear 18 meshing with a larger vertically disposed bevel gear 19 which is rigid with an operating shaft 20. This shaft 20 is journaled within suitable bearings 21 and extends through the inner face of the wall C into the interior of the building, where it is provided with a crank handle 22. By swinging the crank handle and rotating the operating shaft 20 the two sprocket wheels 85 14 are turned in opposite directions and the motion is transmitted from these wheels to the respective shutters so that the latter will be opened or closed, depending upon the direction in which the crank handle 22 is 90 moved. A suitable latch 23 is provided on the crank handle 22, said latch being adapted to engage selected openings 24 in a plate 25 to lock the mechanism and shutters against movement when the shutters have been 95 opened or closed or set in a desired position. The shutters are thus securely locked in an adjusted position, although they can be readily moved by releasing the latch 23 and suitably manipulating the crank handle 22. 100

Having thus described the invention, what I claim as new and desire to secure by Letters Patent, is:—

1. In a shutter opener, the combination with a window casing, shutter and wall, of a shutter hinge, an upright shaft arranged under the shutter hinge and operatively connected thereto, a sprocket wheel on the upright shaft, a second sprocket wheel arranged within the wall, a sprocket chain 105 extending around the two sprocket wheels, an operating lever on the inside of the wall, and gearing between the operating lever and the inner sprocket wheel.

2. In a shutter opener, the combination with a window casing, shutter and wall, of a shutter hinge, an upright shaft having a polygonal lower end and having the upper end thereof operatively connected to the hinge, a sprocket wheel formed with a polygonal opening slidably receiving the upright shaft, bearings for the sprocket wheel, a second sprocket wheel arranged within the wall, a chain extending around the two sprocket wheels, an operating lever projecting from the inner face of the wall, gearing between the operating lever and the second sprocket wheel, and means for locking the operating lever in an adjusted position. 120

3. In a shutter opener, the combination 125

with a window casing, shutter and wall, of a shutter hinge, an upright shaft arranged under the hinge and having a polygonal lower end, flexible shafting operatively connecting the upright shaft to the hinge, a sprocket formed with a polygonal opening slidably receiving the polygonal portion of the upright shaft, bearings for the sprocket, a second sprocket arranged within the wall, a chain extending around the two sprockets, a bevel pinion rigid with the second sprocket, a bevel gear meshing with the bevel pinion, and an operating handle rigid with the bevel gear and projecting from the inner face of the wall.

4. In a shutter opener, the combination with a window casing, shutters and wall, of shutter hinges, upright shafts arranged under the hinges of the respective shutters and operatively connected thereto, a pair of wheels arranged within the wall in a spaced relation and operatively connected to the respective upright shafts, a link having the ends thereof eccentrically connected to the wheels on opposite sides of the axes thereof so that the wheels will turn in unison in opposite directions, an operating lever projecting from the inside of the wall, and gear-

ing between the operating lever and one of the wheels.

5. The combination with a window casing, shutters and wall, of shutter hinges, an upright shaft arranged under the hinge of each shutter and operatively connected thereto, sprocket wheels applied to the respective upright shafts, a second set of sprocket wheels mounted on the interior of the wall, sprocket chains connecting the second sprocket wheels to the first mentioned sprocket wheels of the respective shafts, a link extending between the second sprocket wheels and pivotally connected thereto on opposite sides of the axes thereof so that the sprocket wheels will rotate in unison in opposite directions, a crank shaft projecting from the inside of the wall, and bevel gearing between the crank shaft and one of the second sprocket wheels.

In testimony whereof I have signed my name to this specification in the presence of two subscribing witnesses.

JOHN ROCK, JR.
